UNITED STATES PATENT OFFICE.

MAX FLEISHER, OF NEW YORK, N. Y.

LOCK.

1,359,347.

Specification of Letters Patent. Patented Nov. 16, 1920.

Application filed February 24, 1920. Serial No. 360,772.

To all whom it may concern:

Be it known that I, MAX FLEISHER, a citizen of Russia and a resident of the city of New York, borough of Manhattan, in the county and State of New York, have invented a new and Improved Lock, of which the following is a full, clear, and exact description.

This invention relates to locks, and has for the primary object the production of a lock which is a general improvement over locks at present constructed, and adapted for effective use on doors, safes or other places where locks are needed.

It is also an object of this invention to produce a lock having a plurality of simultaneously actuated bolts working in conjunction with a straddle yoke and partly inclosed keeper.

An additional object is to produce a lock having a simple and efficient roll-back and tumbler catch combination employed to actuate the several bolts.

With the above principal objects and others in view, the invention has relation to the combination and arrangement of simplified lock parts, several variations in design and construction of which appear in the appended claims defining the invention, and one embodiment of which is described in the following specification and illustrated in the accompanying drawings, wherein:

Figure 1 illustrates the lock casing and keeper parts in section to disclose the interior working mechanism of the lock.

Fig. 2 discloses a sectional view as approximately taken on the line 2—2 of Fig. 1.

Fig. 3 shows a cross-sectional view taken on the line 3—3 of Fig. 1.

A lock constructed in accordance with the plans of this invention includes a casing having an integral straddle yoke adapted to fit over and partly inclose a keeper. A plurality of bolts are simultaneously thrust through the straddle yoke and keeper to effect a positive locked position. A bolt frame carries the several bolts, and likewise carries a tumbler catch pivoted thereto. A roll-back is associated with the tumbler catch to operate the lock. Other novel features of construction and advantages of this lock will appear in the following detail specification.

In presenting a more comprehensible and detailed disclosure of my invention, there is

shown a lock casing 6 which has parallel guides 7 made an integral part of the side walls of the casing. These guides function as a track to hold the moving parts in proper working relation, as later seen. A straddle yoke 8 is integrally made on one end of the lock casing. The straddle yoke is provided with bores 9 into which the bolts of the lock move and retract during the locking and unlocking operation thereof. The yoke 8 is formed as a single-piece element integral with the casing 6 by making the web 8, which forms the straddle yoke, in spaced and parallel relation to the front edge of the lock casing. The front edge of the lock casing 6 is likewise provided with bores for the reception of bolts, which allows the bolts to actuate in the lock casing and move forwardly therefrom within the bore 9 of the straddle yoke.

The keeper is made with angle plates 10 to anchor it to the door casing, and this keeper has an integral web 11 projecting from the face of the outer angle plate and registering within the opening of the straddle yoke. The web 11 is provided with bores 12 equal in number to and concentric with the bores of the straddle yoke and the lock casing, all of which are brought into alinement when the lock casing is moved into registry with the web.

A bolt frame 14 has integral lugs 15 slidably confined within the guides 7 so that the frame may be moved back and forth within the lock casing and confined in proper working relation through the agency of the guides supporting and confining the lugs. A number of bolts 16 are fixed to the bolt frame and confined in the bores in the end wall of the casing 6. The bolt frame 14 has an arm 17 extending back from the frame and approximately parallel with the axis of the bolts 16. It is seen how longitudinal movement impressed against the arm 17 will likewise move the bolts 16 outwardly and inwardly relative to the end wall of the lock casing.

A tumbler catch 19 is placed alongside the arm 17 and pivoted on the outer end thereof on a pin 20 passed through both the tumbler catch and the arm. This construction joins the tumbler catch 19 and arm 17 together but permits one end of the tumbler catch to move up and down on the pivot pin 20 relatively to the arm. The tumbler catch is provided with a roll-back notch 21 and a

lock notch 22. A lock pin 23 is anchored in the wall of the casing in line with the tumbler catch 19 and is engageable by the lock notch 22 when the tumbler catch is lifted 5 and driven forward to effect a locked position. One or more springs 24 are fixed to the casing and press downwardly on the upper face of the tumbler catch to restrain it in downwardly limited position. The lock pin 23 is in direct line with the end of the tumbler catch and prevents accidental movement of the lock parts by acting as a stop against the tumbler catch.

A roll-back cylinder 26 is pivotally mounted on the casing and has an upstanding finger 27 lying within the roll-back notch 21. The roll-back cylinder 26 is connected in any suitable manner with the cylinder lock 28 which is mortised within the door upon which the lock is installed. The cylinder lock 28 may be made in any approved design in accordance with recognized lock construction. The cylinder lock 28 has connection with the roll-back cylinder 26 in such a manner that a key when inserted into the lock cylinder will establish a fixed connection between the cylinder 28 and the roll-back 26 in order that said roll-back may be rotated in either direction. A knurled knob 30 is rotatably carried in the wall of the casing 6 and connects with the roll-back 26. The knob 5 may be of any approved construction and is used for opening and closing the lock and door from the inside of the compartment secured by the lock.

In the operation of the lock, a key is inserted in the cylinder lock 28 in the usual manner, and if the proper key is used there is established a joined relation between the roll-back cylinder 26 and the key, which enables the owner of the key to rotate the roll-back 26, thereby swinging the finger 27 upwardly against the lower edge of the tumbler catch to lift the front end of the catch 40 into pivotal motion about the pin 20. After the finger 27 has reached an upright position it moves into engagement against the vertical face of the notch 21, whereupon the finger impresses a forward motion against the tumbler catch which is transmitted to the arm 17 to move the bolts 16 forwardly 45 into the bores 12 of the keeper and bores 9 of the straddle yoke. This bolt action thus anchors the lock casing 6 to the keeper 50 by establishing an overlapping and hooked

engagement between the straddle yoke and the keeper. Simultaneously with the above described action, the lock tumbler 19 drops into engagement with the lock pin 23 by virtue of the lock notch 22 becoming hooked 60 over the pin 23, whereupon the bolts 16 are anchored in secured relation with the keeper and incapable of being forced therefrom.

The device is unlocked by inserting the key in the cylinder lock to establish a connected relation with the roll-back 26, whereupon the tumbler catch 19 is lifted out of engagement with the lock pin 23, which permits the finger 27 to retract the bolts 16 within the lock casing, thus disengaging the keeper to permit the door to be opened.

Having thus described my invention, I desire to secure by Letters Patent:

1. A lock, comprising a casing having guides provided in the form of a track with 75 in the casing, a frame slidably retained in the track, bolts carried by the frame, a tumbler catch pivoted on the frame, said tumbler catch provided with a roll-back notch and a lock notch, a lock pin anchored 80 to the casing in line with the tumbler catch to hold the tumbler catch and connecting bolts in fixed position, and a pair of oppositely turned springs fixed at one end of the casing, and engaging said tumbler catch at 85 the other end so as to maintain said catch into engagement with said pin.

2. A lock comprising a casing having a number of bores made in the end wall thereof, a bolt confined in each bore, a frame connecting the bolts, a guide to hold the frame in correct operating position, an arm attached to the frame, a tumbler catch pivoted on the arm and having notches formed therein, a lock pin anchored to the wall of 90 the casing in line with the tumbler catch to prevent accidental movement of the lock parts, a roll-back cylinder pivoted on the lock casing adjacent the tumbler catch, a finger fixed to the roll-back cylinder and 95 confined in the notch of the tumbler catch to lift said catch above the aforesaid lock pin to manipulate the bolt to retracted and projected position, and a pair of oppositely turned springs fixed at one end to the casing, 100 and engaging said tumbler catch at the other end so as to maintain said catch into engagement with said pin.

MAX FLEISHER.
